(57) **CLAIM**

The ornamental design for a fastener for panel of an automobile, as shown and described above.

DESCRIPTION

FIG. 1 is a perspective view of a fastener for a panel of an automobile according to an embodiment of a present designed article with the view being taken from the right top side looking downwardly;

FIG. 2 is a front view of the fastener of FIG. 1 (a rear view is the same as the front view);

FIG. 3 is a left side view of the fastener of FIG. 1 (a right side view is the same as the left side view);

FIG. 4 is a plan view of the fastener of FIG. 1;

FIG. 5 is a bottom view of the fastener of FIG. 1;

FIG. 6 is a sectional view taken along line 6—6 in FIG. 2;

FIG. 7 is a sectional view taken along line 7—7 in FIG. 2; and,

FIG. 8 is an environmental, sectional view with the broken line showing a portion of structure being for illustrative purposes only and forming no part of the claimed design.
